UNITED STATES PATENT OFFICE

EUGENE S. TAYLOR, OF CHICAGO, ILLINOIS, ASSIGNOR OF ONE-HALF TO HUGH E. YOUNG, OF CHICAGO, ILLINOIS

STORAGE APPARATUS

Application filed December 2, 1931. Serial No. 578,606.

This invention relates to improvements in storage apparatus and, more especially, such apparatus adapted for storing vehicles, for example, motor vehicles and the like.

5 Among the features of my invention is the provision of improved apparatus for storing vehicles in a confined space or area on a substantially horizontal support making very effective use of the space at hand.

10 For the purpose of illustrating my invention, I have shown the same employed in connection with a unit area having certain dimensions. It is obvious, however, that the principles of the invention may be embodied 15 in larger or smaller areas.

By the use of my invention a large proportion of any given space may be effectively utilized for the storage of vehicles and, at the same time, any individual vehicle can be 20 placed in storage or removed therefrom with a relatively small amount of movement of other stored vehicles.

Other features and advantages of my invention will appear more fully as I proceed 25 with my specification.

In those forms of devices embodying the features of my invention shown in the accompanying drawings—

Figure 1 is a top plan view of a unit area of 30 storage space showing my improved apparatus; Fig. 2 is an enlarged fragmentary top plan view showing the means for laterally shifting vehicles; Fig. 3 is a view taken as indicated by the line 3 of Fig. 2; Fig. 4 is a view 35 taken as indicated by the line 4 of Fig. 2; Fig. 5 is a view taken as indicated by the line 5 of Fig. 2; Fig. 6 is a view taken as indicated by the line 6 of Fig. 2; Fig. 7 is a fragmentary perspective view showing the bearings for the 40 rollers upon which the vehicles are shifted laterally; Fig. 8 is a vertical sectional view of said rollers; Fig. 9 is a view similar to Fig. 2 showing other means for laterally shifting the vehicles; Fig. 10 is a view similar to Fig. 5 showing the means for laterally shifting vehicles employed in Fig. 9; and Fig. 11 is a view taken as indicated by the line 11—11 of Fig. 10.

As shown in the drawings, Fig. 1 indicates 50 a unit of storage space or area, for example,

a single floor of a building of sufficient size to accommodate substantially sixteen vehicles (when filled to its maximum capacity) in rank and file formation, four vehicles to each rank and four to each file. This unit of space or 55 floor area I have indicated, in general by 10, the walls of the same being indicated by 11.

Numerals 12, 12 may indicate doors or openings affording access to the floor 10. In the event that the floor 10 is above the ground 60 level, 13, 13 may indicate elevators.

For convenience I shall designate the four files A, B, C, and D and the ranks 1, 2, 3 and 4. Each of the doors 12 furnishes access to one of the files and a vehicle may 65 be moved on its own wheels in any file from one rank to another both backwardly and forwardly. My storage apparatus is so constructed to permit vehicles to be thus moved longitudinally on their own wheels from one 70 rank to another in any file.

In order to utilize a relatively large proportion of the storage space and still permit any particular vehicle to be removed from the same, it is necessary or desirable to provide means permitting lateral shifting of a stored vehicle from one file to another in any rank. One of the features of my invention is the provision of such means so constructed as not substantially to interfere with the longitudinal movement of the stored vehicles on their own wheels from rank to rank 75 in any file. This means permitting such lateral shifting includes two transverse rows of rollers countersunk in the supporting surface in each rank, said rows adapted to support the front and back wheels of a stored vehicle. Since the construction and operation of these means are substantially the same 80 in each rank, it is necessary to describe in detail but one. In the first rank, these two transverse rows of rollers are indicated in general by 14 and 15, the former adapted to support the back wheels of a vehicle and the latter, the front wheels. I have indicated 85 the individual rollers by 16. The ends of these rollers are supported in bearings 17 formed in the upper edges of transversely arranged supporting members 18 (see Figs. 7 and 8). In Fig. 6, 19, 19 indicate the front 100

wheels of a vehicle supported on the rollers 16 in the roll 15. It is to be particularly noted that the rollers 16 are countersunk in the surface 10 so that their upper edges 5 are substantially flush with the surrounding floor surface 10. They are also sufficiently small and placed sufficiently close together so that they do not substantially interfere with movement of vehicles longitudinally 10 on their own wheels over the floor or supporting surface 10. That is, a vehicle may be easily driven or otherwise moved on its own wheels longitudinally forwardly and backwardly across the transverse rows of 15 rollers 16.

In the operation of the apparatus, vehicles may be driven into any file and located in any rank desired. It is contemplated that four vehicles be placed in the fourth rank but 20 that only three be placed in ranks 1, 2 and 3. In other words, one file is left entirely vacant with the exception of the fourth rank. The space will thus accommodate 13 cars when filled to its maximum capacity. When 25 thus occupied by cars, any car desired may be removed by laterally shifting cars behind it to clear the file that it occupies. For example, as shown in Fig. 1, 20, 21, 22, 23, 24, 25 and 26 may indicate stored cars. 30 It will be seen that car 23 may be driven backwardly through the length of its file. In the event that it is desired to remove car 24, however, it is necessary to shift car 20 laterally from file B to file A in order to clear 35 file B behind car 24. This shifting is accomplished by moving car 20 laterally on the rollers 16. This may be done by merely pushing the car sideways, the roller 16 serving as anti-friction devices or conveyors permitting the lateral shifting of the car. This 40 lateral shifting may be accomplished in any suitable manner. If desired, the cars can be laterally shifted manually. I prefer, however, to provide mechanical means for laterally shifting the car and will describe the 45 same in the following paragraph.

I have here shown mechanical means for laterally shifting the cars, said means comprising laterally shiftable pushers adapted 50 to engage a vehicle to be shifted, and means for laterally moving the pushers. Since the construction and operation of these devices are similar, it is necessary to describe but one. I have here shown these devices as comprising 55 a pair of side bars or pushers 27, 27 separated sufficiently to permit a car to pass between the same. These bars 27, 27 have their ends attached to uprights 28 mounted on the bars 29 supported on the rollers 30, 30. These 60 bars 29 operate in the transverse grooves 31 in the floor 10.

The following means are provided for shifting the bars 27. Such means include 65 endless cables 32 sunk in the floor operating over the pulleys 33 and 34. The pulley 33

is an idler and the pulley 34 is mounted on the shaft 35 driven by the motor 36 through a suitable speed-reducing gear 37. The motor 36 is reversible so that the shaft 35 may be driven in either direction. The driving 70 pulleys 34 are loosely mounted on the shaft 35 and adapted to be locked thereto by clutches 38 operated by means of the operating levers 39. It is to be understood that there is a cable for each pair of bars 27, 27. 75 It may be stated that each pair of bars 27, 27 forms a sort of cage for a vehicle. This cage may be shifted laterally as desired, the bars 27, 27 engaging the wheels 19, 19 of the vehicle to shift the same laterally over the 80 rollers 16. Attachment of the bars 27 to the cables 32 is effected by means of the members 40 having their upper ends attached to the bars 27 and their lower ends clamped to the cable 32 (see Fig. 5). The cables 32 are arranged under the floor surface 10 and the members 40 operate in suitable slots 41 in the floor. The shaft 35, motor 36, control levers 39, and so forth, may be arranged at one side of the storage floor area 10 in a depressed 85 pit 10a.

In Figs. 9, 10 and 11 I have shown different means for laterally shifting the vehicles. Instead of employing the depressed rollers 16, I use a carriage or dolly comprising the two 90 parallel channels 50-50, supported on small flanged rollers 51-51 operating on the transversely arranged tracks 52-52. For laterally shifting the carriages, I may employ cables 53 similar to the cables 32 above described. Each of these cables is provided with a pair 95 of members 54 similar to the members 40, above described. These members 54 are adapted to engage the channels 50 of the carriages to shift the same laterally. The channels 50 are close enough to the floor to permit a vehicle to be very easily driven onto the same or over the same. The ends of the channels may be curved downwardly to a slight extent as indicated by 50a. That is, the channels 50 do not substantially interfere with the longitudinal movement of stored vehicles on their own wheels from rank to rank in any 100 file.

It is to be particularly noted that all the vehicles in any one rank may be shifted laterally by merely shifting the end vehicle. For example, as shown in Fig. 1, if the three vehicles 20, 21 and 22 are to be shifted laterally (upwardly as viewed in Fig. 1) all that is necessary is to move the pushers 27 engaging the vehicle 22. This pusher will engage the other pushers and other vehicles so that all three vehicles will be moved by merely moving the vehicle 22. This is true also in the event that dollies such as shown in Figs. 9, 10 and 11 are employed. In such case all that is necessary is to shift the dolly carrying the vehicle 22. This in turn will shift the ve- 115 120 125 130

hicles 20 and 21 and the dollies upon which the same are resting.

While I have shown and described certain embodiments of my invention, it is to be understood that it is capable of many modifications. Changes, therefore, in the construction and arrangement may be made without departing from the spirit and scope of the invention as disclosed in the appended 10 claims, in which it is my intention to claim all novelty inherent in my invention as broadly as permissible, in view of the prior art.

What I regard as new, and desire to secure by Letters Patent, is:

15 1. Storage apparatus including; a supporting surface adapted to accommodate vehicles stored in rank and file formation; two transverse rows of rollers countersunk in the supporting surface in each rank, said rows 20 adapted to support the front and back wheels of a stored vehicle and permit lateral shifting of the stored vehicle thereon; a pusher adapted to engage the sides of a car to shift the same laterally, said pusher including a 25 pair of bars sufficiently spaced apart to permit a vehicle to pass longitudinally therebetween; and means for laterally moving said pusher.

2. Storage apparatus including; a supporting surface adapted to accommodate vehicles stored in a plurality of files; and means for laterally shifting a vehicle from one file to another, said means including two transverse rows of rollers countersunk in the supporting surface, said rows adapted to support the front and back wheels of a vehicle and permit lateral shifting thereon from one file to another, a pusher adapted to engage the sides of a car to shift the same laterally, 35 said pusher including a pair of members sufficiently spaced apart to permit a vehicle to pass longitudinally therebetween, and means for laterally moving said pusher.

3. Storage apparatus including; a supporting surface adapted to accommodate vehicles thereon in a plurality of files; two transverse rows of rollers countersunk in the supporting surface, said rows extending from one file to another and adapted to support the front and back wheels of a stored vehicle and permit lateral shifting of the same thereon from one file to another; a pusher adapted to engage the sides of a car to shift the same laterally, said pusher including a pair of members sufficiently spaced apart to permit a vehicle to pass longitudinally therebetween; and means for laterally moving said pusher.

4. Storage apparatus including; a supporting surface adapted to accommodate vehicles stored in rank and file formation; two transverse rows of rollers countersunk in the supporting surface in each rank, said rows adapted to support the front and back 65 wheels of a stored vehicle and permit lateral

shifting of the stored vehicle thereon; a transversely movable carriage arranged below the surface; a pusher mounted on said carriage extending above the supporting surface and adapted to engage a part of a car 70 to shift the same laterally, said pusher normally positioned to permit free longitudinal movement of a car past the same; and means for laterally moving the carriage.

5. Storage apparatus including; a supporting surface adapted to accommodate vehicles in a plurality of files; two transverse rows of rollers countersunk in the supporting surface, said rows extending from one file to another and adapted to support the 75 front and back wheels of a vehicle and permitting transverse shifting of the same thereon from one file to another; a transversely movable member arranged below the supporting surface; a pusher carried by said 80 member extending above the supporting surface and adapted to engage a part of a car to shift the same transversely, said pusher normally positioned to permit free longitudinal movement of a car past the same; and means for transversely moving said transversely movable member.

In witness whereof, I have hereunto set my hand and seal, this 10th day of November, 1931.

EUGENE S. TAYLOR.
